(57) **CLAIM**

An ornamental design for a shoe upper, as shown and described.

DESCRIPTION

FIG. 1 is a perspective view of an upper for a shoe, a characteristic feature of which resides in the woven fabric exterior surface;

FIG. 2 is a side view of the upper from an outside edge of the shoe;

FIG. 3 is a side view of the upper from an inside edge of the shoe;

FIG. 4 is a front view of the upper;

FIG. 5 is a back view of the upper; and,

FIG. 6 is a top view of the upper.

The phantom lines showing portions of a shoe in FIGS. 1-6 are for illustrative purposes only and form no part of the claimed design.
